RAZOR BLADE SHARPENER

Gote E. Bergman, New York, N. Y.

Application October 22, 1947, Serial No. 781,463

2 Claims. (Cl. 51—158)

1

This invention relates to razor blade sharpeners. It is an object of the present invention to provide a razor blade sharpener which has a rigid frame construction for containing a slide and side portions including a sharpener piece which will be engaged each time the slide is slid from one end of the frame to the other.

It is another object of the present invention to provide a razor blade sharpener having a slide which will alternately cause the sharpening of opposite sides of the blades as the slide is respectively moved first in one direction and then in the opposite direction.

Other objects of the present invention are to provide a razor blade sharpener which is of simple construction, inexpensive to manufacture and efficient in operation.

For other objects and for a better understanding of the invention, reference may be had to the following detailed description taken in connection with the accompanying drawing, in which

Fig. 1 is a top perspective view of the razor blade sharpener embodying the features of the present invention.

Fig. 2 is a side elevational view of the sharpener shown in Fig. 1.

Fig. 3 is a perspective view of the slide with the cover part raised to permit the insertion of the blade or the removal of the same from the slide.

Fig. 4 is an illustrative view showing the blade in engagement with the sharpener pieces and free of the slide.

Fig. 5 is a transverse cross-sectional view taken generally on line 5—5 of Fig. 4.

Fig. 6 is an illustrative view showing the razor edges being drawn across the sharpener pieces.

Fig. 7 is a side elevational view of the diagonally ground sharpener pieces.

Referring now to the figures, 10 and 11 represent guide rods over which a slide 12 is operated. The opposite ends of the guide rods 10 or 11 are embedded in end pieces 13 and 14 which may be made of plastic or other suitable material. At the opposite sides of the guides 10 and 12 are thin strips 15 and 16 which extend from one end piece to the other and are embedded in the pieces 13 and 14 to be rigidly retained between the same. The slide 12 includes a bottom part 17 having holes therethrough for receiving the guide rods 10 and 11 and a cover or hinged part 18 fixed to the main part 17 to be pivoted over the top of the same and upon a blade 19 to retain the same in place. The part 17 has a central

2

raised shelf portion 21 for receiving the blade 19 and extending upwardly from the shelf portion 21 are pins 22 over which the blade is extended. These pins 22 enter holes 23 in the cover 18 as the cover is brought downwardly over the blade 19. The cover 18 also has a central raised portion so as to lie flat upon the blade 19 and whereby the sides of the blade or the cutting edges thereof will extend outwardly from the portions 21 and 24 in order that they will be brought to bear upon sharpener pieces 25 carried on the strips 15 and 16. There are two sharpener pieces 25 so that simultaneously both edges of the blade will be sharpened at the same time. The sharpener pieces as shown in Fig. 7 are diagonally ground or formed or twisted so that as the blade 19 is drawn first in one direction it will be drawn first over the top of the sharpener piece and then on its return movement will be drawn across the bottom of the sharpener piece. The strip pieces 15 and 16 will give a little under the pressure of the blade or will twist slightly so that the sharpener pieces will be adapted to the blade edges being sharpened.

25 The top of the end piece 13 has a finger or thumb opening 27 and roughened portions 28 to provide a good grip by the thumb and fingers of the hand. The slide 12 has a thumb or finger opening 29 and also roughened portions 31.

30 While various changes shall be made in the detail construction, it shall be understood that such changes shall be within the spirit and scope of the present invention as defined by the appended claims.

35 Having thus set forth and disclosed the nature of this invention, what is claimed is:

1. A razor blade sharpener comprising guide rods transversely spaced from one another, end pieces connected to the opposite ends of the guide 40 parts, a slide adapted to be extended over the guide rods and having separable parts, means projected from the parts for retaining the razor blade so that its edges extend laterally therefrom and are accessible from both bottom and top 45 sides, thin spring strips extending from one end piece to the other and located respectively upon opposite sides of the guide rods, and sharpener pieces carried upon the spring strips and adapted to be engaged by the opposite side edges of the 50 razor blade as the same is moved back and forth along the guide rods.

2. A razor blade sharpener comprising guide rods transversely spaced from one another, end pieces connected to the opposite ends of the guide 55 rods, a slide adapted to be extended over the guide

rods and having separable parts, means projected from one of the parts for retaining the razor blade so that its edges extend laterally therefrom and are accessible from both bottom and top sides, thin spring strips extending from one end piece to the other and located respectively upon opposite sides of the guide rods, and sharpener pieces carried upon the spring strips and adapted to be engaged by the opposite side edges of the razor blade as the same is moved back and forth along the guide rods, said sharpener

pieces being longitudinally diagonally ground whereby first one side of the blade edge will be engaged by one face of the sharpener piece on movement of the slide in one direction and then 5 the opposite face of the side edge of the blade will be engaged by the opposite face of the sharpener piece on the return movement of the slide and blade along the guide rods.

GOTE E. BERGMAN.
